Julian Polackoff
ATTORNEY

UNITED STATES PATENT OFFICE.

NATHAN BERLINER, OF NEW YORK, N.Y.

CORSELET.

Application filed January 16, 1928. Serial No. 246,975.

This invention relates to a new and useful device in the nature of a corselet such as worn by women in place of the usual corsets, for the purpose of maintaining the figure of the wearer and at the same time permit of free movement.

The object of the invention is to provide a corselet embodying a means of easily and readily applying the said corselet to the wearer, in a manner which will tend to stretch the corselet so as to secure proper application conforming to the wearer.

Another object of the invention is to provide a means of easily and readily applying the said corselet in a manner which will render it practically impossible for the corselet to become partially or totally unapplied or disengaged, due to the movement of the wearer or to a tight fitting corselet.

Fig. 1 is a front elevational view of my improved corselet.

Fig. 2 is a rear view thereof.

Fig. 3 is a fragmentary view showing in particular the open position of the separable fastener device.

Fig. 4 is an enlarged fragmentary view showing the upper portion of the separable fastener device.

Fig. 5 illustrates a further development of the eyelet member as embodied in my improved device.

Fig. 6 is a sectional view taken on the line 6—6 of Fig. 5.

Fig. 7 illustrates the adjustable hook as embodied in the further development of my improved device.

Fig. 8 is a sectional view taken on the line 8—8 of Fig. 7.

As here embodied my improved corselet comprises a front and rear body member 10 and 11, preferably of rectangular shape, having stitched, sewn or otherwise secured thereto, at the upper portions thereof, upper side members 12 and 13. Elastic members 14, 15, 16 and 17, preferably formed flared, i. e., having their lower edges somewhat wider than their upper edges, and secured to the front and rear members, below the upper side members 12 and 13, and are secured to the lower side members 18 and 19. The lower side members 18 and 19 are secured to the lower edges of the said upper side members 12 and 13, respectively.

Suitable tape 20, edging or the like, such as ordinarily used to conceal the stitching or sewing, may be sewn to my improved

corselet so as to cover such stitching or sewing as above stated and as is required to secure the various members of my improved device together. It is understood that the above described construction is such as will provide a corselet embodying any desired certain figure lines, such as may be in vogue from line to line i. e., I do not necessarily limit my invention to a non-form corselet, such as would be desirable to young women, or children.

In Figs. 3 and 4, I have shown separable fastener members 21 and 22 secured to and extended from the tapes 24, which extend vertically, or longitudinally from the lower edge of my improved corselet to within proximity of the top edge thereof. The said tape 24 is sewn to the reinforcing strip 25, and which are secured to the side of the above mentioned elastic member 19. It is understood that an opening extending from the lower edge of the corselet to within proximity to the top edge thereof exists, which is closed by the slide 26, which engages and locks the said separable fastener members when the slide 26 is pulled downwardly, and which unlocks the separable fastener members when the slide is pulled upwardly. It is understood that the tape 24 is secured to the inner side of the front member 10, and at the edge thereof adjacent to the said elastic member 19.

The above described construction is such as will permit the wearer of my improved device to draw or pull the slide downwardly, which requires a natural pulling motion and does not interfere with or materially change the body lines, or form of the wearer. The latter mentioned downward movement, or pull causing a natural straightening out effect which will substantially reduce the diametrical form of the wearer, thus allowing the body to fit into my improved corselet, which will readily apply itself to the wearer. While this downward movement contracts the body, an upward movement would expand it, therefore if the corselet would be closed during an upward movement it would be more difficult to squeeze the body into a predetermined small space.

The conventional hook 27' is secured to the lower portion of the strip 25 and is adapted to receive the eyelet 27 of the slide 26, as a means of holding the separable fasteners in a closed or open position.

The usual garter supports 28 are secured to and extended downwardly from the lower edge of my improved corselet, as may be desired to support the garters of the person wearing my improved device. One of the said supports, designated by the reference numeral 29, is secured to the lower portion of the strip 25 below the hook 27' for the purpose of causing a downward pull on the said hook, which will obviously insure the engagement of the hook in the eyelet of the said slide, as a means of holding the separable fastener in a closed or locked position.

In the construction of my improved device, I employ a single enclosing member, 30, secured to and extended from the edge of the above mentioned front member, as a means of covering or enclosing the separable fastener device. The said single enclosing member is practically self aligning and has no companion member to foul or to interfere with the fastening device and further renders the said device easily and readily operable, as same is not in the way during such operation.

In Figs. 5 and 6, I have shown the eyelet 27 provided with an extended element 31 formed or bent in front of the aperture formed therein to receive the hook 27'. The extremity of the extended element 31 is somewhat depressed, at its central portion as at 32, as a means of providing a limited space or clearance between the said extremity and the body portion of the said eyelet, so as to securely hold the hook in engagement therewith.

In Figs. 7 and 8, I have shown the hook 27' secured to the rivets 33 and 34 and extended therefrom. The rivets 33 and 34 have formed therein notches 35 and 36, respectively. The said hook is of spring steel construction, so as to normally urge the notches 35 and 36 in engagement with and

any desired opposite ones of the serrations 37, formed in the plate member 39, adjacent to the openings 40 and 41 formed in the plate member 39. The central portion of the plate member having its lower extremity formed or bent hook shaped, as at 43, as a means of preventing the said hook 27' from being separated from the plate member. The plate member 39 has formed therein adjacent to its periphery apertures 44, as a means of securing the said plate member to the lower portion of the above mentioned strip 25. The above described construction is such as will permit the said hook to be held in any desired position on the plate member 39, as may be required to secure the desired engagement of the said hook on the eyelet 27.

It is to be understood that my invention may be applied to corsets or other similar undergarments.

Having thus described my invention, what I claim as new and desire to secure by United States Letters Patent is:—

In a corselet of the class described, a separable fastener device adapted to close an opening formed in the said corselet, said opening extending vertically from the bottom edge thereof within proximity of the top portion thereof, said separable fastener device adapted to be locked by a downward pull on a slide adapted to engage the said separable fastener device, a holding member adapted to engage the said slide as a means of holding the said separable fastener in a locked position, and a garter support secured so to and extended from the said corselet below the said holding member as a means of insuring the engagement of the said holding member.

In testimony whereof I have affixed my signature.

NATHAN BERLINER.
